UNITED STATES PATENT OFFICE.

WILLIAM K. WILLIAMS, OF GRAND RAPIDS, MICHIGAN, ASSIGNOR TO
GRAND RAPIDS SHOW CASE COMPANY, OF GRAND RAPIDS, MICHIGAN, A CORPORATION OF MICHIGAN.

SHOW-CASE.

No. 834,699.

Specification of Letters Patent.

Patented Oct. 30, 1906.

Application filed July 21, 1905. Serial No. 270,617.

To all whom it may concern:

Be it known that I, WILLIAM K. WILLIAMS, a citizen of the United States, residing at Grand Rapids, in the county of Kent and State of Michigan, have invented certain new and useful Improvements in Show-Cases; and I do hereby declare the following to be a full, clear, and exact description of the invention, such as will enable others skilled in the art to which it appertains to make and use the same.

My invention relates to improvements in show-cases, and more particularly to improvements in the show-case shown in patent to me, No. 788,979, dated May 2, 1905.

The object of my present invention is to provide means whereby the joints between the front and end plates may be adjusted and kept tight, to provide a more rigid structure, and to provide the device with various new and useful features; and it consists, in addition to the structure shown in said patent, of means for adjusting and holding the end plates, consisting substantially of a flexible tongue inserted in the groove of the back frame near the bottom thereof and a headless screw engaging said tongue and forcing the same against the rear edge of the plate, whereby the plate is forced in close contact with the front glass at the bottom and also held immovable, thus securing a tight joint and a rigid structure, as will more fully appear by reference to the accompanying drawings, in which—

Figure 1 is an end elevation of a show-case with my invention embodied therein; Fig. 2, an enlarged detail of a portion of the same, showing my improvement in vertical section; and Fig. 3, a horizontal section of the same.

Like numbers refer to like parts in all of the figures.

1 represents the end, 2 the front, and 3 the top, of a show-case, said end, front, and top being of plate-glass. 4 is a felt packing-strip between the edges of the end plate 1 and the front and top plates. 5 represents the back of the case, which is provided with a groove 9

to receive the rear edge of the end plate 1, all as shown in Patent No. 788,979.

My improvement consists of the addition of a headless screw 6, inserted in a horizontal opening in the back 5 and engaging a flexible strip 8, preferably of metal, inserted in the bottom of the groove 9 and adapted to yieldingly engage the edge of the plate 1 to force the same toward the plate 2. 7 is a nut embedded in the back 5, with which the screw engages. By turning this screw inward the strip 8 is forced against the plate 1 and moves the same forward to closely contact the front plate 2 and at the same time rigidly hold the lower part of the plate from moving, and thus insures a rigid and substantial structure regardless of any shrinking or swelling of the woodwork of the back or close fitting of the same to the edge of the plate. The flexible strip 8, interposed between the screw and the edge of the plate, prevents the screw from grinding and breaking the plate.

Having thus fully described my invention, what I claim, and desire to secure by Letters Patent, is—

1. In a show-case, the combination of a front plate, an end plate having its front edge in engagement with the front plate, a back frame having a groove to receive the rear edge of the end plate, a flexible strip in the groove, and a screw in the back frame and engaging the said strip to force the same against the rear edge of the end plate.

2. In a show-case, the combination of a front plate, an end plate having its front edge engaging the front plate, a back frame having a groove to receive the rear edge of the end plate, a flexible strip and a nut embedded in the back frame at the bottom of the groove, and a headless screw within the back frame and engaging the nut and flexible strip.

In testimony whereof I affix my signature in presence of two witnesses.

WILLIAM K. WILLIAMS.
